Patented Dec. 3, 1918.

Inventor
Harold Rountree
By his Attorney
Samuel E. Darby

UNITED STATES PATENT OFFICE.

HAROLD ROWNTREE, OF KENILWORTH, ILLINOIS.

CHAIR.

1,286,421.

Specification of Letters Patent. Patented Dec. 3, 1918.

Application filed November 4, 1915. Serial No. 59,539.

To all whom it may concern:

Be it known that I, HAROLD ROWNTREE, a citizen of the United States, residing at Kenilworth, county of Cook, State of Illinois, have made a certain new and useful 5 Invention in Chairs, of which the following is a specification.

This invention relates to chairs, settees or the like.

10 The object of the invention is to provide a chair which is simple in structure, durable, and economical of manufacture.

A further object of the invention is to provide a chair, settee or the like, which may 15 be tilted backwardly to any desired degree for convenience or comfort.

A further object of the invention is to provide means for preventing a chair, settee or the like, from overturning due to the 20 backwardly tilted position thereof.

Further objects of the invention will appear more fully hereinafter.

The invention consists of the construction, combination, location, and relative arrangement of parts, all as will be more fully hereinafter set forth, as shown by the accompanying drawing, and finally pointed out in the appended claims.

Referring to the drawing,—

30 Figure 1 is a view in side elevation, partly broken, of a chair embodying my invention.

Fig. 2 is a view in front elevation of the same, with the chair in upright position.

Fig. 3 is an enlarged detail view, parts 35 being in section.

Fig. 4 is a sectional view taken on the line 4, 4, Fig. 3.

The same part is designated by the same reference numeral wherever it occurs 40 throughout the several views.

It is among the special purposes of my present invention to provide a chair which may be tilted backwardly to any desired degree for the purpose of reclining therein, 45 and in connection therewith to afford means for the rear legs or supports of the chair to be shifted or inclined rearwardly in accordance with the degree of tilting of the chair body.

50 It will be understood, however, while I have mentioned my invention as applied to chairs, and will hereinafter describe a chair constructed in accordance therewith, the invention is equally well adapted to be applied 55 to settees, couches, or similar articles of furniture used for similar purposes.

Referring to the drawings, I show one simple embodiment of my invention as applied to a chair wherein I employ the usual chair back 1, and seat 2, rigidly secured with 60 respect to each other. Curved arm rests 3 are suitably secured to the back 1 and the seat 2. If desired, and as shown, the front legs or supports 4, for the chair seat may be formed in one piece with the arm rests 3, 65 but my invention in its broad scope is not to be limited or restricted in this respect.

Pivoted secured to the seat back 1, by suitable means, such as bolts 5, are the rear legs or supports 6, a projection 7 on the upper ends of the same being adapted to pass directly beneath the lower edge of the curved arm rests in a groove 8 therein, as shown, when the legs are rocked about their pivots 5. In accordance with my invention 75 I propose to project the rear legs or supports rearwardly when a tilted position of the chair is desired, thereby securing the tilting of the back and seat and at the same time affording the necessary rear support 80 for the same to prevent the chair from tilting completely over backwardly, and in connection therewith to employ means for suitably locking the rear legs or supports in any desired degree of rearward projection. A 85

simple arrangement for accomplishing this result is shown wherein the groove 8 of the under surface of the arm rests 3 is provided with openings 9 projecting from the grooves into the arm rest as shown, spaced apart in 90

any desirable manner, according to the degree of tilting desired, and positioned radially upon said arm rest with respect to the pivots 5 of the legs 6 on correspondingly opposite sides of the chair seat 2. Normally 95

maintained to project out of the top end of the legs 6, by means of a spring 10, is a bolt 11. A thumb screw 12 passes through a slot 13 in the outer side of each of the rear legs 6, and is attached to the spring bolt 11, as 100 shown, so that when the thumb screw 12 is depressed, in the slot 13, it carries with it to its depressed position, against the action of the spring 10, the bolt 11, withdrawing the same out of the hole 9, and allowing the 105

leg 6 to be rocked about its pivot to the desired position thereof, the bolt 11, due to the pressure of the spring 10, automatically locking the leg in its position, when the end thereof comes in line with one of the holes 9. 110 If desired and as shown, the opening 13 in the outer surface of the legs 6, may be in-

closed by a plate 15, secured to the legs by means of screws 16.

While I have shown and described specific means for securing the locking of the legs and the degree of tilting of the chair structure, it will be understood that my invention, in its broad scope, is not to be limited thereto, as many other arrangements will readily occur to those skilled in the art with-
10 out departing from the broad scope of my invention as defined in the claims.

Having now set forth the objects and nature of my invention, and a structure embodying the principles thereof, what I claim
15 as new and useful and of my own invention, and desire to secure by Letters Patent, is,—

1. In a chair frame structure, the combination with a back therefor, of arm rests provided with grooves on their under surfaces, 20 front and rear legs for said frame, said rear legs being pivotally mounted on said frame and provided with means at the ends thereof for traveling in said grooves of said arm rests when said rear legs are rocked about

their pivots, and means for locking said rear legs in position. 25

2. In a chair frame structure, the combination with a back therefor, of arm rests provided with grooves on their under surfaces, spaced holes in said grooves, front and 30 rear legs for said frame, said rear legs being pivotally mounted on said frame and provided with means at the ends thereof for traveling in said grooves when said legs are rocked about their pivots, spring bolts also 35 carried in the ends of said rear legs, and normally operating to engage in said holes in said grooves to lock said rear legs into position.

In testimony whereof I have hereunto set 40 my hand in the presence of the subscribing witnesses, on this 27th day of October A. D. 1915.

HAROLD ROWNTREE.
